PRUNING DEVICE

George W. Newman, Kansas City, Mo.

Application March 18, 1940, Serial No. 324,590

4 Claims. (Cl. 30—245)

My invention relates to improvements in pruning devices, adapted for pruning branches of trees or shrubs, or for insertion into the ground to sever roots.

My invention relates to the type of pruning devices in which two jaws are provided with co-operating shearing portions, one of the jaws being mounted upon a suitable support, the other jaw being movable to and from the closed position.

It is well known that when a knife blade is operated by hand to sever a branch or piece of wood, it is much easier to sever the branch if a teetering or rocking motion is imparted to the blade, while the blade is being forced through the wood.

One of the objects of my invention is the provision, in a pruning device of the type described, of novel means by which while the movable jaw is being moved to the closed position, it has also imparted to it a teetering or back and forth rocking movement, similar to the teetering of the knife blade, as above described.

Another object of my invention is the provision of additional novel means for exerting an amplifying leverage in forcing the movable jaw to the closed position.

Still another object of my invention is to provide a novel pruning device, which is composed of relatively few parts, is simple, cheap to make, strong, durable, not likely to get out of order, which is easy to operate, and which is very efficient in its operation.

The novel features of my invention are hereinafter fully set forth and described.

In the accompanying drawings, which illustrate the preferred embodiment of my invention,

Fig. 1 is a side elevation, partly broken away, of my improved pruning device, the parts being shown in solid lines in the positions occupied by them when the movable jaw is in the fully open position, the parts being shown in dotted lines in their positions when the movable jaw has been advanced toward its closed position.

Fig. 2 is an elevation, partly broken away, of the other side of the pruning device, with the parts shown as they are when the jaws are closed.

Fig. 3 is a side elevation looking at one side of the socket portion of the support.

Fig. 4 is a side elevation of the socket portion disposed at right angles to that occupied by it as shown in Fig. 3.

Fig. 5 is a top view of the socket portion.

Fig. 6 is a view similar to Fig. 1, showing the

parts as they are positioned when the movable jaw has been moved half way toward the closed position.

Fig. 7 is an elevation view of the parts shown in Fig. 6, looking in the direction indicated by the arrow in Fig. 6.

Fig. 8 is a plan view of the fixed jaw looking at one side thereof.

Fig. 9 is an edge view of the fixed jaw.

Fig. 10 is a side view of the movable jaw.

Fig. 11 is an edge view of the movable jaw. Similar characters of reference designate similar parts in the different views.

My improved pruning device has a support comprising, as shown, a tubular socket portion 1 in the lower end of which is fastened one end of a handle 2.

In the flattened upper portion 3 of the socket portion 1 is fastened by bolts 4 the lower end of 20 a fixed jaw 5, having at its upper end an oblique shearing portion 6, which inclines, as shown in Fig. 1, downwardly to the right. The jaw 5 is rectangular in cross section, and is shown in detail in Figs. 8 and 9.

25 A movable jaw 7, shown in detail in Figs. 9 and 10, is disposed, as shown in Fig. 1, at the right of the fixed jaw 5. It has in longitudinal alignment with the jaw 5 an offset shearing portion 8, having a cutting edge 9. When the jaw 7 is 30 fully opened and fully closed, as shown respectively in solid lines in Fig. 1, and in Fig. 2, the cutting edge 9 is parallel with the shearing portion 6 of the fixed jaw 5. The object to be severed by the jaws is disposed between them, 35 when the jaw 7 is in the fully open position, as shown in solid lines in Fig. 1.

Mechanical means support the movable jaw 7 on which it may be moved from the fully open position to the closed position, said means while 40 moving the jaw 7 toward the closed position imparting to the jaw also a teetering movement by which the jaw, while moving toward the closed position, rocks back and forth on the article that is being severed, thus greatly aiding in the severing of the article, in the same manner as does teetering of a knife blade when it is used to sever a branch.

Such mechanical means, in the specific form shown and described, comprises the following 45 described parts.

A member, comprising a lever 10, is bifurcated at one end, the two arms 11 of which bifurcation embrace between them the lower end of the jaw 7 and the jaw 5 to which the two arms 11 are 50 pivoted respectively on two axes by two bolts 12.

Two members 12', comprising two parallel links, at opposite sides respectively of the jaw 7, are pivoted to the jaw 7 and the jaw 5, between the lever arms 11 and the cutting edge 9, on two axes comprising two bolts 13.

The distance between the axes 13 is greater than the distance between the axes 12 of the lever arms 11. By means of this arrangement, when the outer end of the lever 10 is swung downwardly, the jaw 7 will be moved downwardly and have imparted to it a teetering movement, in which the cutting edge 9 will, while moving to the closed position, rock in one direction against the object that is being severed, until the cutting edge 9 reaches the middle position, as shown in Fig. 6. It will then rock in the other direction until the cutting edge 9 contacts with the shearing portion 6, at which time it will be again parallel therewith.

This teetering movement of the cutting edge 9 against the object will enable the cutting edge 9 to easily sever the object.

For swinging the lever 10 downwardly, to close the jaw 7, the outer end of the lever has attached to it an operating cable 14.

For moving the jaw 7 to the open position, shown in Fig. 1, means are provided, which, as shown as a specific embodiment in Figs. 1, 6 and 7, consists of a wire spring 15 coiled around a bolt 16 having a threaded portion fitted in a threaded hole 17 in the jaw 5. The bolt 16 extends through the jaw 5 and has fitted on it a lock nut 18, at the side of the jaw 5 opposite to the side at which is disposed the spring 15. One end of the spring 15 is extended through a hole 19 in the head of the bolt 16. The other end portion of the spring 15 bears against the under side of the adjacent link 12', the tension of the spring being such as will yieldingly resist the closing movement of the jaw 7, and will move the jaw 7 to the closed position, when the lever 10 is permitted to swing upwardly. The tension of the spring 15 may be varied by proper rotary adjustment of the bolt 16.

In the operation of my improved pruning device, the object to be severed is disposed between the jaws 5 and 7, while the jaws are open, as shown in solid lines in Fig. 1. The cable 14 is then pulled downwardly, thus swinging downwardly the lever 10, which draws downwardly the jaw 7.

While the jaw 7 is moving to the middle position, shown in Fig. 6, the difference in distance between the axes 13 of the links 12' and that between the axes 12 of the lever arms 11, will cause the cutting edge 9 of the jaw 7 to have imparted to it a teetering movement in one direction, as will be observed by the different angles between the cutting edge 9 and the shearing portion 6 of the jaw 5, in Fig. 6.

Continued closing movement of the jaw 7, from the middle position, shown in Fig. 6, to the closed position, shown in Fig. 2, will cause the cutting edge 9 to rock in the opposite direction until the cutting edge 9 impinges against the shearing portion 6, at which time the cutting edge 9 and the shearing portion 6 will again be parallel with each other, as in the fully open position, shown in solid lines in Fig. 1.

Upon releasing the cable 14, the spring 15 will swing the parts back to the fully open position. By having the cutting edge 9 of the movable jaw 7 disposed above the fixed jaw 5, when the handle has its outer end up, the cutting edge will be

drawn downwardly against the upper side of the branch to be cut, and the weight of the branch will assist in the cutting operation, the lower fixed jaw 5, at the time bearing against the under side of the branch.

By having the lever 10-11 pivoted to the jaw 5 below the link 12', the lever can have greater length, and, therefore, a greater leverage without having it interfere with the engagement of the upper cutting jaw 7 with the branch to be cut, than would be the case, were the lever pivoted to the jaw 5 above the place of pivoting of the link 12' to the jaw 5.

Many modifications of my invention, within the scope of the appended claims, may be made without departing from the spirit of my invention.

What I claim is:

1. In a pruning device, a support, two jaws having cooperating shearing portions one having a cutting edge, one of said jaws being fixed on said support, the other jaw being movable to and from the closed position, a lever pivoted on two axes to said jaws respectively for moving said movable jaw to said closed position, a member pivoted on two axes to said jaws respectively between said lever and the shearing portion of said movable jaw, the distance between the axes of said member being greater than the distance between the axes of said lever, and resilient means for moving said movable jaw to the open position.

2. In a pruning device, a support, two jaws having cooperating shearing portions, one jaw being fixed to said support, the other jaw having its shearing portion provided with a cutting edge, a lever pivoted on two axes to said jaws for moving said movable jaw to the closed position when swung in one direction, means for so swinging said lever, a member pivoted to said two jaws on two axes respectively intermediate of said lever and said cutting edge, the distance between the axes of said member being greater than the distance between the axes of said lever, and resilient means for moving said movable jaw to the open position.

3. In a pruning device, a handle, a fixed lower jaw fastened to the outer end of said handle, and adapted, when the outer end of the handle is up, to bear against the under side of a branch to be cut, a movable upper jaw having a cutting edge above said lower jaw and adapted to bear against the upper side of the branch, when said handle is so positioned, a link pivoted respectively on two axes to said jaws, and a lever pivoted respectively to said two jaws on two axes, the distance between the axes of said link being different from the distance between the axes of said lever.

4. In a pruning device, a handle, a fixed lower jaw fastened to the outer end of said handle, and adapted, when the outer end of the handle is up, to bear against the under side of a branch to be cut, a movable upper jaw having a cutting edge above said lower jaw and adapted to bear against the upper side of the branch, when said handle is so positioned, a link pivoted respectively on two axes to said jaws, and a lever pivoted respectively to said jaws on two axes disposed below the first named axes, the distance between the axes of said link being different from the distance between the axes of said lever.

GEORGE W. NEWMAN.
